CLAIM

The ornamental design for a pan organizer, substantially as shown and described.

DESCRIPTION

FIG. 1 is a perspective view of a pan organizer showing my new design;

FIG. 2 is a right side view, the left side view being a mirror image thereof;

FIG. 3 is a front view thereof;

FIG. 4 is a rear view thereof;

FIG. 5 is a top view thereof;

FIG. 6 is a bottom view thereof;

FIG. 7 is a front view of a single divider removed from the pan organizer;

FIG. 8 is a right side view, the left side view being a mirror image thereof;

FIG. 9 is a bottom view thereof; and,

FIG. 10 is a top view thereof.

The broken lines show unclaimed subject matter only and form no part of the claimed design.
